(57) **CLAIM**

The ornamental design for a karaoke controller with microphone, as shown and described.

DESCRIPTION

FIG. 1 is a front perspective view of a karaoke controller showing my new design;

FIG. 2 is a front plan view of the karaoke controller of FIG. 1;

FIG. 3 is a back plan view of the karaoke controller of FIG. 1;

FIG. 4 is a left side view of the karaoke controller of FIG. 1;

FIG. 5 is a right side view of the karaoke controller of FIG. 1;

FIG. 6 is a top view of the karaoke controller of FIG. 1;

FIG. 7 is a bottom view of the karaoke controller of FIG. 1; FIG. 8 is a front perspective view of the karaoke controller of FIG. 1 showing an encoded cartridge being removed; and, FIG. 9 is a front perspective view of the karaoke controller of FIG. 1 showing an encoded cartridge removed.

The broken line showing of the encoded cartridge is for illustrative purposes only and forms no part of the claimed design.
